DESIGN.

S. WALEGA.

CURTAIN POLE HOLDER.

54,709.

APPLICATION FILED AUG. 14, 1919.

Patented Mar. 9, 1920.

UNITED STATES PATENT OFFICE.

STANLEY WALEGA, OF CHICAGO, ILLINOIS.

DESIGN FOR A CURTAIN-POLE HOLDER.

54,709.

Specification for Design. Patented Mar. 9, 1920.

Application filed August 14, 1919. Serial No. 317,625. Term of patent 7 years.

To all whom it may concern:

Be it known that I, STANLEY WALEGA, a citizen of Poland, residing at Chicago, in the county of Cook and State of Illinois, have invented a new, original, and ornamental Design for a Curtain-Pole Holder, of which the following is a specification, reference being had to the accompanying drawing, forming part thereof.

In the drawing,

Figure 1 is a top plan view of the improved curtain bracket,

Fig. 2 is a side elevational view with the shade roller bearing shown in dotted lines, and

Fig. 3 is a front elevational view thereof with the shade roller bearing shown in dotted lines.

I claim:

The ornamental design for a curtain pole holder, as shown.

STANLEY WALEGA.
